UNITED STATES PATENT OFFICE.

LOUIS BOEPPLER, OF OAKLAND, CALIFORNIA, ASSIGNOR TO THE PARAFFINE COMPANIES, INC., OF SAN FRANCISCO, CALIFORNIA, A CORPORATION OF DELAWARE.

GAME RACK.

Application filed December 8, 1923. Serial No. 679,352.

To all whom it may concern:

Be it known that I, LOUIS BOEPPLER, a citizen of the United States, and a resident of the city of Oakland, county of Alameda, 5 State of California, have invented a new and useful Game Rack, of which the following is a specification.

My invention relates to games and particularly to a rack for holding the tiles used 10 in the Chinese game mah jongg.

An object of my invention is to provide a game rack which can be folded into a pocket size package, and at the time of play can be folded into stable form.

15 Another object of my invention is to provide a very cheap rack for use in playing mah jongg.

The invention possesses other objects and features of advantage, some of which, with 20 the foregoing, will be set forth in the following description of the preferred form of my invention which is illustrated in the drawings accompanying and forming part of the specification. It is to be understood that 25 I do not limit myself to the showing made by the said drawings and description, as I may adopt variations of the preferred form within the scope of my invention as set forth in the claims.

30 Referring to the drawings:

Figure 1 is a perspective view of the unfolded sheet.

Figure 2 is a perspective view of the rack in folded position.

35 Figure 3 is a sectional view of the rack taken in a plane perpendicular to its longitudinal axis. A game tile is shown in dotted lines.

Broadly considered, my invention comprises a generally rectangular sheet of 40 fibrous material, such as cardboard, scored longitudinally to facilitate folding into prismatic form, and scored transversely to permit folding into a pocket size package. 45 When folded, one side of the prism extends beyond the adjacent side and forms a ledge on which the game pieces or tiles rest. The extended side is provided with slits thru which pass complementary tabs formed integral with the sheet. These tabs serve as 50 legs to support the rack and also as means for holding the sheet in folded form during the time of play.

In detail, my invention comprises a generally rectangular sheet of card-board with

a transverse crease 3 in the center of the sheet. When folded on this line a flat package is formed which can be carried conveniently in a pocket. There are many types of wooden racks on the market but such racks 60 cannot be carried about easily. It is difficult to play the game mah jongg without a rack. The tiles are easily tipped over, which exposes the player's hand to his opponents, the playing combinations are not 65 so easily kept together and the tiles being in vertical position are not so easily read. The wooden racks are cumbersome and heavy and are frequently left behind just on account of their inconvenience. My invention 70 provides a rack of regulation size which is light in weight and when folded on the scoring 3 makes a package which can be carried in a pocket.

The sheet is provided with two parallel 75 longitudinal creases 4 and 5, which divide the sheet into three areas, 6, 7 and 8 and which facilitate the folding of the sheet into prismatic form. The area 8 is wider than the other two areas and is provided 80 with slits 9 disposed near the outer edge of the sheet and parallel to the fold 4. Disposed on the outer edge of the area 6 and formed integral with the sheet are tabs 11 85 complementary to the slits 9.

To form the game rack of my invention the sheet is folded along the creases 4 and 5, the tabs 11 being passed thru the slits 9. The space between the slits 9 and the outer 90 edge of the area 8 extend beyond the adjacent side of the prism and forms a ledge 12. After being passed thru the slits the tabs are bent backwardly slightly, as shown in Figure 3. This keeps them from being disengaged from the slits by the resiliency of 95 the folded sheet, and also prevents the weight of the tiles on the ledge 12 from pushing the lower edge of the prism downwardly from the tabs and allowing the rack to collapse. The tabs not only serve as 100 locks to make the rack stable but also provide legs. The legs improve the angle on which the tiles lie and give the player a better view of his hand.

I claim:

1. A game rack comprising a sheet of fibrous material folded into prismatic form, and means for holding the sheet in folded position.

2. A game rack comprising a substantially 110

rectangular sheet of fibrous material folded into a triangular prism, and means for holding the sheet in folded position.

3. A game rack comprising a substantially rectangular sheet of fibrous material folded into a prism and provided with tabs and complementary slits, the tabs when in engagement with the slits, serving to hold the sheet in folded position and to provide legs for the rack.

4. A game rack comprising a sheet folded in prismatic form, one side of the prism extending past the adjacent side and forming a ledge on which the game pieces may rest.

5. A game rack comprising a sheet of fibrous material having longitudinal creases therein to facilitate folding into prismatic form and a transverse crease to permit the formation of a pocket size package.

6. A game rack comprising a sheet folded in prismatic form, one side of the prism extending past the adjacent side and forming a ledge on which the game pieces may rest,

a series of slits in said extending side, complementary tabs on the adjacent side, adapted when passed thru the slits to form legs to support the rack and hold the sheet in folded position.

7. A game rack comprising a substantially rectangular sheet of fibrous material having parallel longitudinal creases dividing the sheet into three areas, one of the outside areas being wider than the remaining areas and provided with slits, the opposite edge of the sheet being provided with tabs complementary to said slits, said sheet being adapted to be folded along the said creases to form a triangular prism with the wider area extending beyond the adjacent side of the prism to form a ledge and the tabs engaged in the slits to form legs to support the rack and to form locks to prevent unfolding thereof.

In testimony whereof, I have hereunto set my hand.

LOUIS BOEPPLER.
